UNITED STATES PATENT OFFICE.

FREDERICK S. ANABLE, OF BROOKLINE, MASSACHUSETTS, ASSIGNOR TO NATIONAL BINDING MACHINE COMPANY, OF NEW YORK, N. Y., A CORPORATION OF NEW YORK.

STRIP-SERVING DEVICE.

1,221,002.

Specification of Letters Patent. Patented Mar. 27, 1917.

Application filed June 23, 1915. Serial No. 35,981.

To all whom it may concern:

Be it known that I, FREDERICK S. ANABLE, a citizen of the United States, and a resident of Brookline, in the county of Norfolk and 5 State of Massachusetts, have invented an Improvement in Strip-Serving Devices, of which the following description, in connection with the accompanying drawings, is a specification, like characters on the drawings 10 representing like parts.

This invention relates to devices or apparatus for supplying strips of paper or the like employed for wrapping or binding packages, or for use as labels of any desired 15 length, and has particular reference to that type of apparatus employing a support for a coil of paper strip previously gummed and then dried, and having provisions for moistening the gum upon the strip as the latter is 20 drawn from its coil. It is apparent that an ungummed strip of paper or the like may be employed, in which case the moistening device for the strip, suitably positioned with respect thereto, would contain an adhesive 25 instead of water.

This application is in part a division of my co-pending application for strip serving device, Serial No. 449,320, filed August 19, 1908, and in part is a continuation thereof.

30 In order that the principle of the invention may be clearly understood, I have disclosed a single embodiment thereof in the accompanying drawing, wherein—

Figure 1 is a side elevation, partially in 35 section, of the preferred embodiment of my invention;

Fig. 2 is a plan view, partially in section, of the moistener shown in Fig. 1 and adjacent parts; and

40 Fig. 3 is a vertical sectional view of the moistener shown in Fig. 2.

Referring more particularly to the drawings, I have therein represented the strip support at 1, it being of any suitable construction and being preferably a case wherein in a roll of paper may be suitably supported and tensioned. Herein it is represented as mounted upon a base 2.

I contemplate the provision of means 50 whereby strip moistening means acts to sever the strip and preferably to sever a predetermined length thereof, which length may, if desired, be varied. One form of my invention is herein shown. Upon the base 2 is 55 represented a reservoir 3 having fixedly supported in opposite walls thereof an axle 4

having loosely mounted thereon a barrel 5. One end of a coil spring 6 is connected at 7 to the inner surface of the barrel and is connected to said axle at 8, the construction being such that the barrel is rotated forwardly during the moistening operation and is returned by the spring 6 after the severing operation. Mounted between flanges 9 of the barrel is a strip of wicking or other fibrous 65 material 10.

Preferably sleeves 11 are provided to maintain the barrel in proper position. Adjustably mounted upon opposite faces of the barrel 5 are disks 12, 13 connected by a severing blade 14, which is suitably spaced from the barrel and if desired may be provided with openings to prevent undue disturbance of the water in the tank or reservoir during the rotation of the barrel. The disk 13 is 75 suitably guarded as represented in Fig. 1 and is circumferentially slotted, as indicated at 15, to receive a set screw 16, whereby the disks and blade 14 may be circumferentially 80 adjusted, so that the blade 14 may be positioned when the moistener is at rest at any desired distance from the severing point. The barrel 5 is provided with a stop 17 adapted normally to contact with an overhanging lip 18 upon the tank or reservoir. 85

If, with the parts positioned as represented in Fig. 1, the strip be drawn forwardly and be retained in close frictional engagement with the moistener, the barrel 5 will 90 rotate therewith without slipping and will revolve the blade 14 into severing relation with the strip, thereby severing a predetermined length thereof. If a shorter length than the indicated maximum be desired, it is necessary merely circumferentially to adjust the disks 12, 13 in the direction of the arrow shown in Fig. 1, thereby positioning the blade 14 when at rest nearer the strip severing point. If desired, I may employ any suitable means acting when the strip 100 is drawn upon to force the strip into tight frictional engagement with the surface of the moistener, thus insuring unison in movement of the strip and the moistener, and preventing slipping therebetween. For this 105 purpose, I may employ a lever or levers carrying at one end a cross bar adapted to be engaged by the strip when drawn upon, and at the other end a cross bar adapted to be projected by movement of the 110 levers against the surface of the moistener, such as shown in my Patent No. 897,510,

September 1, 1908. If desired, one or both of such cross bars may be formed as an anti-frictional roll or sleeve.

So far as I am aware, I am the first to provide strip severing means carried by a moistener and particularly by a movable moistener, and desire to claim the same broadly. I am also the first so far as I am aware to provide means operated by the moistener to sever a predetermined or variable length of strip, and desire to claim the same broadly.

Devices have heretofore been proposed for severing predetermined lengths of strip but requiring generally considerable complication of parts. My invention is one of marked simplicity and few parts, and I may readily adjust or alter the same so as to sever different lengths of strips within wide limits, inasmuch as the moistener barrel may be of any suitable or desired diameter.

Having thus described one illustrative embodiment of my invention, I desire it to be understood that although specific terms are employed, they are used in a generic and descriptive sense and not for purposes of limitation, the scope of the invention being set forth in the following claims.

30 Claims.

1. A strip serving device comprising a strip support, a moistener, and strip severing means carried by said moistener.
2. A strip serving device comprising a strip support, a rotary moistener and a severing blade carried by said moistener.
3. A strip serving device comprising a strip support, a moistener, and strip severing means carried by the moistener and operated by strip moistening movement to sever the strip.
4. A strip serving device comprising a strip support, a rotary moistener, a severing blade carried by said moistener and movable through the reservoir of the moistener into strip severing relation.
5. A strip serving device comprising a strip support, a movable moistener, and means operated by and movable with the moistener to sever a predetermined length of strip.
6. A strip serving device comprising a strip support, a rotary moistener, and an adjustable severing blade carried by said moistener.
7. A strip serving device comprising a strip support, a movable moistener, means operated by and movable with said moistener to sever a predetermined length of strip, and means to vary said predetermined length.
8. A strip serving device comprising a strip support, a moistener, the surface whereof travels with the strip during service draft thereon, and a severing blade car-

ried by the moistener and movable into strip severing relation.

9. A strip serving device comprising a strip support, a moistener having a surface movable with the strip during draft thereon, and a severing blade movable with said moistener into severing relation to the strip. 76

10. A strip serving device comprising a strip support, a moistener having a surface movable with the strip during draft thereon, a severing blade movable with said moistener into severing relation to the strip, and means to adjust the position of said blade. 75

11. A strip serving device comprising a strip support, a moistener having a surface adapted to travel with the strip during the service draft thereon, a severing blade carried by said moistener, and spring means to move said moistener in a direction opposed to the direction of service draft upon the strip. 80

12. A strip serving device comprising a strip support, a rotary moistener, and a severing blade carried by said moistener and circumferentially adjusted thereabout. 90

13. A strip serving device comprising a strip support, a rotary moistener circumferentially movable with the strip, spring means to move the moistener in the opposite direction, and strip severing means carried by the moistener. 95

14. A strip serving device comprising a strip support, a rotary moistener, a reservoir wherein the same is mounted, and a severing blade carried by said moistener and movable through the contents of the reservoir in the strip severing relation. 100

15. A strip serving device comprising a strip support, a rotary moistener, means to guide the strip into moistening relation thereto, and means carried by the moistener to sever a predetermined length of strip. 105

16. A strip serving device comprising a strip support, a rotary moistener, means to guide the strip into moistening relation thereto, and an adjustable severing device carried by said moistener and movable in the serving operation into strip severing relation. 110

17. A strip serving device comprising a strip support, a rotary moistener, spring means to rotate the moistener in one direction, limiting means for said spring actuated movement of the moistener, and means synchronized in movement with the moistener to effect strip severance. 115

18. A strip serving device comprising a strip support, a rotary moistener, spring means to rotate the moistener in one direction, and strip severing means synchronized in movement with the moistener to sever the strip. 125

19. A strip serving device comprising a strip support, a rotary moistener, spring means to rotate the moistener in one direction, 130

tion, strip severing means synchronized in movement with the moistener to sever the strip, and means to adjust said severing means, thereby to effect the severance of a 5 predetermined, variable length of strip.

20. A strip serving device comprising a strip support, a rotary moistener adapted to be moved in one direction by draft upon the strip, a spring to rotate said moistener in 10 the opposite direction, and a strip severer carried by the moistener.

21. A strip serving device comprising a strip support, a moistener 10 and severing means 14 carried by the moistener.

15 22. A strip serving device comprising a strip support, a rotary moistener 10, and severing means 14 mounted thereon and rotatable therewith.

23. A strip serving device comprising a strip support, a rotary moistener 10, a 20 severing blade 14 mounted on said moistener, and means 15, 16 to vary the position of said severing blade upon the moistener.

24. A strip serving device comprising a strip support, a rotary moistener, means to 25 rotate the moistener in one direction, and strip severing means movable with the moistener into severing relation with the strip.

In testimony whereof, I have signed my 30 name to this specification, in the presence of two subscribing witnesses.

FREDERICK S. ANABLE.
